UNITED STATES PATENT OFFICE.

OTTO B. WEDELL, OF ELGIN, ILLINOIS.

EYEGLASS-CHAIN REEL.

1,141,855.

Specification of Letters Patent. Patented June 1, 1915.

Application filed July 13, 1912. Serial No. 709,185.

To all whom it may concern:

Be it known that I, OTTO B. WEDELL, a citizen of the United States, residing at Elgin, in the county of Kane and State of Illinois, have invented new and useful Improvements in Eyeglass-Chain Reels, of which the following is a specification, reference being had to the accompanying drawings, forming a part thereof.

10 The purpose of this invention is to provide an improved eye-glass holder of the nature of a chain reel having in some respects a more stable bearing for the reel and a more compact and secure construction than devices heretofore common.

It consists in the elements and features of construction shown and described as indicated in the claims.

In the drawings: Figure 1 is an axial section of a reel embodying this invention. Fig. 2 is a section at the line, 2,—2, on Fig. 1. Fig. 3 is a section at the line, 3,—3, on Fig. 1. Fig. 4 is a detail rear side elevation of the device showing the mode of securing the attaching pin. Fig. 5 is a detail section at the line 5,—5, on Fig. 4. Fig. 6 is a detail section at the line 6,—6, on Fig. 3.

The structure shown in the drawings comprises a casing consisting of a cupped front element, 1, and a flanged back plate, 2, said back plate having a cylindrical flange, 2^a, formed upon it by infolding upon itself at a short distance inward from the outer circumference the blank from which such back plate is formed, as seen at 2^b, and folding and stretching off into cylindrical form at right angles to the blank, a portion to form said flange, 2^a. The cupped front member, 1, is designed to make a snug telescopic fit outside of the flange, 2^a, as seen in Fig. 1, the casing being separable at this point, but the parts being nevertheless held securely enough to prevent accidental separation. The back plate has a central aperture, 2^t, counter-bored at the inner side to seat and center with respect to it a shaft bearing block, 3, which is circular in form except that it has a notch, 3^a, in its periphery, said notch extending through a segment of something less than 90° of the circumference of

the block and terminating at one end abruptly,—that is, so that its end is approximately radial with respect to the block, and from that end sloping off in the direction of a chord of a segment, as seen in Fig. 55 2. The block, 3, is made rigid with the back plate, 2, being soldered in the counter-bore around the central aperture, 2^t, of said back plate, and it is itself centrally apertured to afford one bearing for the barrel 60 shaft, 4. The barrel comprises the peripheral channel portion, 5, in which the chain is wound and the circular web, 6, which is made of sheet metal having struck up at its center an annular flange, 6^a, constituting a 65 hub which is the inner boundary of the spring chamber, said chamber comprising the annular space between said flange, 6^a, and the inner circumference of the channel member, 5, of the barrel. Said flange, 6^a, is 70 of such inner diameter as to fit tightly upon the shaft, 4, which thus rotates with the barrel as an integral part thereof. The total dimension of the web, 6, in the direction of the axis of the barrel,—that is, the 75 length of the hub flange, 6^a, is about half the width of the barrel and there is thus left between the block, 3, and the inner circumference of the barrel an annular chamber. This chamber is occupied by a plate, 80 9, circular in form, and fitting tightly within the drum so as to operate as integral therewith, and having a central aperture, 9^a, which receives the bearing block, 3, the latter fitting loosely therein so that the drum 85 rotates without friction of the plate, 9, on said block, 3. Said plate 9, has leading from its central aperture in which the bearing block, 3, is situated, diametrically-opposite recesses forming pockets, 9^b, which 90 are each of such dimensions as to accommodate one of the locking tumblers, 7, which are initially lodged in said pockets and are of suitable diameter to pass out of the pockets into the notch, 3^a, of the block, 3, 95 when, as the barrel revolves, said pockets in turn come around to that notch. The plate, 9, is cut away at one corner of each of said notches, as seen at 9^c, to form a face concave toward the block, 3, and curved with 100

a radius substantially equal to that of the tumblers; and the above-mentioned abrupt end of the notch, 3^a, is also curved with the same radius, the center of curvature of said 5 face, 9^d, being at the same distance from the axis of the shaft as the center of curvature of said abrupt end of the notch, 3^a, so that when a tumbler passes out of one of the 10 pockets, 9^e, into the notch, 3^a, it may become engaged and fit between the said concave face, 9^d, at the corner of a pocket and the concavely curved abrupt end, 3^b, of the notch, as seen in Fig. 2, and by this means 15 the tumblers serve as locking means to permit the rotation of the drum in one direction, and to lock it against rotation in the opposite direction.

Upon the inner face of the cupped front member, 1, of the casing, there is soldered 20 concentrically therewith a cupped collar, 8, centrally apertured to receive the end of the shaft, 4, whereby said collar becomes the bearing for that end of the shaft. The cylindrical flange, 8^a, of this cupped collar encompasses the hub, 6^a, of the drum, the interior diameter of the collar being enough 25 greater than the outer diameter of the hub to afford space between the two to accommodate the end of the spring, 10, the said 30 flange of the cupped collar being notched at 8^b, to receive the spring which is folded back upon itself at its inner end so that an extreme end portion, 10^a, stands between the hub, 6^a, and the said flange 8^a of the cupped 35 collar, as seen in Fig. 3, and thus the said cupped collar constitutes the means for securing the inner end of the spring, 10, to the casing. For securing the outer end of the spring to the barrel, the blank for forming 40 the web, 6, is made with a radially projecting tongue or finger, 6^b, and the metal of the web is severed for a short distance inward of its circumference at each side of the finger so that said finger may be folded 45 up at right angles to the plane of the web at the inner end of the slits, and thereby it is caused to project from the web at a distance inward from the circumference of the latter a little greater than the thickness 50 of the spring, said finger being in length substantially equal to the width of the spring and serving as a means of hitching to the drum the outer end of the spring which is folded inward upon itself to form a hook, 55 10^b, for engagement of the finger as seen in Fig. 3.

11 is the chain which is wound in upon the channelled periphery, 5, of the barrel. For engaging it with the drum the latter is 60 provided with an aperture, 5^c, at the bottom of its channel, adjacent to one of its flanges, and the blank from which the web, 6, of the drum is formed has in addition to the

finger, 6^b, another finger, 6^d, which in the blank projects radially, and in the completed 65 drum is folded so as to project transversely of the web just inside the inner circumference of the channelled periphery member, 5, of the barrel across the aperture, 5^c. This finger will be sufficiently flexible so that it 70 can be sprung inward to uncover the aperture, 5^c, and permit an end link of the chain inserted through said aperture, 5^c, to be hooked onto the finger, thus securing the chain to the barrel. To provide space in 75 which this finger, 6^d, may protrude past the aperture, 5^c, the plate, 9, is cut away at its periphery for a short distance, as shown at 9^e, the cavity, thus made, being large enough 80 for convenient manipulation of the finger, 6^d, of the chain, and engaging the latter with the former. From the barrel the chain runs out through an aperture, 1^a, in the cylindrical flange of the cupped front member, 1, of the casing. In order that when the 85 chain is fully drawn out; that is, entirely unwound from the barrel, the point at which the pockets, 9^e, of the plate, 9, of the barrel stand shall be sufficiently removed from the locking point shown in Fig. 2 to permit 90 and require a little backing up of the barrel for locking,—this being necessary in order that there may be still a little range of unwinding movement for releasing the barrel from locked position,—it may be necessary 95 to adjust the position of the plate, 9, about the axis to properly relate the position of the pockets, 9^e, to the point at which the chain is hitched to the barrel; and for this purpose the recess, 9^e, in the periphery of 100 the plate, 9, is extended somewhat circumferentially as shown in Fig. 2.

12 represents a pin of common form for securing the device to the garment of the user. For attaching this pin readily to the 105 back plate, 2, of the casing, the latter has struck out from its substance, three staple-formed loops, 2^c, 2^d and 2^e, offset sufficiently from the outer surface of the plate to admit through them outside said outer surface, the 110 back bar, 12^a, of the pin, and to adapt said back bar to be thus inserted it is formed from a blank, as seen in Fig. 2, having at one end two laterally-projecting lugs, 12^b, which are folded up opposite each other to 115 receive between them the pivoted end of the pin. The other end of said back bar is formed suitably to constitute the hook, 12^c, for engaging the point of the pin. The lugs, 12^b, may be folded up and the pin secured 120 between them before it is applied to the reel, and the back bar being then inserted through the loops, 2^c, 2^d and 2^e, in the order named, and protruding below the last mentioned loop the full extent of the portion of its 125 length which comprises the hook, 12^c, said

protruding portion may be folded up below said last mentioned loop and thereby the pin is secured upon the back plate.

I claim:—

5 1. In a chain reel device, in combination with a casing, comprising a front plate and a back plate adapted to be engaged with each other; bearing members mounted rigidly on the inner faces of the front and back plates, respectively, said bearing members having journal bearings alined with each other; a chain-drum and a spring which resists its rotation in one direction, said drum having a peripheral chain-channel and a 10 web medially situated in respect to the width of said channel, and a journal to which said web extends and is rigidly secured, the journal being mounted rotatably in said bearings, whereby one of said journal bearings 15 may be extended along the journal substantially to the web.

2. In a chain reel, in combination with a casing comprising a front plate and a back plate, adapted to be engaged with each other; bearing members mounted rigidly on said front and back plates, respectively, having journal bearings alined with each other; a chain-drum comprising a peripheral chain-channel; a web medially situated with respect to the channel and a central hub portion extending off one side of the web, concentric with the chain-drum journal; a journal member to which said web extends and to which it is secured by said hub extending there-along, the journal member being mounted rotatably in said bearing members, one of said bearing members being in cup form having its flange extending concentrically about the drum hub, and the other 30 being extended along said journal member substantially to said medial web; a helical spring connected at its inner end to and adapted to be coiled about said cup flange in the annular space at one side of the web, 35 and having its outer end connected to the drum, and a locking device situated at the opposite side of the web in the annular space between the chain channel and the bearing at that side.

50 3. In a chain reel, in combination with a cupped casing member having a centrally seated cup-shaped shaft bearing and having its cup flange provided with a notch, a chain drum having its shaft mounted in said bearing and comprising a peripheral member for winding the chain, a hub portion fast on the shaft, and a web connecting them, the flange of the shaft bearing being substantially larger than the hub and thus inclosing an 55 annular space around said hub, and a spring coiled about said cupped bearing adjacent to the web having its outer end engaged with the drum and its inner end hooked into the

said notch with the end of the hook occupying the said annular space.

65

4. In an eye-glass holder in combination with a casing comprising front and back plates, bearing members mounted upon the inner faces of said plates, respectively, having journal bearings alined with each other; a chain drum comprising a web situated medially with respect to the width of the drum periphery; a journal member mounted rotatably in said bearings and to which the web extends, the latter having a hub extended off 70 one side along the journal member for securing of the drum to the journal; a spring located at that side of the web in the annular space between said hub and the drum periphery, and means by which said 75 spring is connected at the inner end to the bearing member and at the outer end to the drum, the bearing member at the other side of the web being extended along the journal member substantially to said web, and having 80 a peripheral notch; a member located in the annular space at that side of the web between said bearing member and the drum periphery and rigid with the drum; said member having a slot in its inner circumference opening toward the periphery of the bearing member, and a tumbler element located in the slot and adapted to enter the notch in the periphery of the bearing member.

95

5. In an eye-glass holder, the combination of a back plate, a cup-shaped member secured to the same and co-acting therewith to provide an inclosure, a notched bearing member secured to the inner portion of the 100 back plate, a bearing member secured to the inner portion of the cup, a reel having a portion rotatably mounted within both of said bearing members, and a spring which resists its rotation in one direction, a slotted 105 element on the reel adapted to travel adjacent to the periphery of the notched bearing member, and a tumbler element within the slot of the slotted member serving to co-act with the notch of the notched member 110 for locking purposes, substantially as described.

6. In an eye-glass holder, the combination of a casing comprising a front plate and a back plate adapted to be engaged with each other having, respectively, fixed shaft bearings which are alined with each other when the casing members are assembled, a drum for the chain comprising a peripheral portion for winding the chain, a hub portion having rigidly extending journals at either side rotatably mounted in the bearings of the casing members, respectively, and a web portion connecting said hub with the peripheral portion intermediate the width of 115 the latter, a spring coiled about one of said

120

125

fixed bearings adjacent to said web of the drum and having its inner end engaged with said bearing and its outer end engaged with the drum, the other shaft bearing having a 5 peripheral notch, an annular lock plate fixed in the drum at the other side of its web surrounding said notched bearing, said lock plate having a pocket opening toward the periphery of said notched bearing, and an 10 unattached locking tumbler contained in said

pocket and adapted to pass therefrom into the notch for locking the reel against rotation in the casing.

In testimony whereof, I have hereunto set my hand at Chicago, Illinois, this 6th day of 15 July, 1912.

OTTO B. WEDELL.
